UNITED STATES PATENT OFFICE.

ALFRED RÜGLER, OF BERLIN-ERKNER, GERMANY, ASSIGNOR TO THE FIRM OF ELEK-
TROTECHNISCHE FABRIK SCHMIDT & CO., OF BERLIN, GERMANY.

DRY GALVANIC CELL.

Application filed September 26, 1925, Serial No. 58,769, and in Germany October 3, 1924.

The chemical process at work in a galvanic dry cell, when current is being generated, produces an increase in volume of the electrolyte, which has been thickened 5 with meal, starch or the like, leading, for instance, in the ordinary sal-ammoniac electrolytes, to solid and liquid reaction products such as zinc salts and water, on the one hand, and on the other to gases, such 10 as ammonia and hydrogen.

It happens then that if there is not sufficient room for the expanding electrolyte, it escapes to the outside through the gas-discharge openings or else springs the casting 15 when it is a hermetically sealed cell or explodes the holder. If a free space is left above the electrolyte for its expansion the electrolyte shows a tendency to spread over the entire upper surface of the depolarization 20 electrode, covering the latter completely. This prevents more or less the escape of gas for instance ammonia produced within the cell and causes the voltage of the charged cell to quickly fall off so that 25 its useful life is very appreciably diminished.

The drawbacks just described are, according to the present invention, removed by a device which, on the one hand, shuts off the 30 upper surface of the depolarization electrode to the electrolyte as it rises and on the other hand, thereby facilitates a permanent gas exchange between the electrode and the outer air. It consists of a hollow body of 35 cylindrical or other shape, either open below or suitably perforated which is forced (shrunk) or otherwise closely secured on the upper part of the depolarization material surrounding the carbon pole. This 40 body can also, in the making of the depolarization electrodes, be fixedly secured to the latter. The electrolyte as it rises is now taken up by the suitably sized space between the outer wall of this added body and 45 the zinc vessel, while the inner space of the body which may be subdivided if desired is utilized for the circulation of the gas.

The gas exchange (communication) hereby rendered possible with the external atmosphere, is still further promoted by the insertion of two, or in certain cases more, ventilation pipes of different lengths into the cover seal. The size of these is to be determined by arranging that the shorter 55 ones terminate below the seal while others

reach nearly to the free upper surface of the depolarization material. It has been found that such arrangement of pipes of different lengths not only allows the escape 60 of gases produced within the cell but causes at the same time a circulation of atmospheric air which increases the depolarizing effect of the depolarization electrode.

A constructional form of the cell is shown 65 in the drawing.

Figure 1 representing a longitudinal section, through the cell and

Figure 2 a cross section.

1 denotes the carbon rod surrounded in the usual way, by the depolarization material 2. The space between this depolarization electrode and the zinc vessel 3 is filled up as usual with the thickened electrolyte 4. The body fitted thereon consists of two co-axial cylinders 5 and 6 of any suitable 70 insulating material, these being attached to each other by stays or struts, after the manner of wheel spokes. This body is forced (pressed) on to the depolarization material being closed off from above by a 75 disc 8 on which the seal 9 is fused.

Ventilation pipes are led through the latter and through the disc, the number of these being in this particular case limited to two. The pipe 10 reaches to just under 80 the closing disc 8 while the pipe 11 terminates a little way above the depolarization 85 material 2.

By the closing off of the depolarization upper surface against the electrolyte which 90 is effected by the arrangement just described and by the employment at the same time of vigorous ventilation, a very considerable rise is effected in the efficiency of the cell.

What I claim is:—

1. A primary dry galvanic cell comprising an outer metallic tubular electrode and an inner compound electrode consisting of a carbon rod and a surrounding mass of depolarizing material and a thickened electrolyte between said outer tubular metallic electrode and said mass of depolarizing material, a gas chamber being provided above said mass of depolarizing material said chamber having a circumferential wall 100 adapted to prevent the electrolyte from overflowing the upper surface of the depolarizing material, so as to allow free escape of gas through substantially the whole upper surface of the depolarizing mass, the cell 105 110

being closed at the top, and openings through the closed end to allow the escape of gas from said gas chamber.

2. A dry galvanic cell comprising an outer metallic tubular electrode and an inner compound electrode consisting of a carbon rod and a surrounding mass of depolarizing material and a thickened electrolyte between said outer tubular metallic electrode and said mass of depolarizing material, a hollow chamber being provided above said

mass of depolarizing material said chamber having a circumferential wall adapted to prevent the electrolyte from entering into said chamber, the chamber being closed at the top, the closure having inserted therein ventilation tubes ending within the chamber at different distances from the top of the depolarizing material. 15

In testimony whereof, I affix my signature. 20

DR. ALFRED RÜGLER.
